UNITED STATES PATENT OFFICE.

FRANK J. GENSLEY, OF VICTOR, IOWA.

WASHING MACHINE.

Application filed July 2, 1923. Serial No. 449,076.

My invention relates to a washing machine having for its object a very compact machine, simple and effective in construction and operation, whereby the proper amount 5 of air is compressed and forced through the washing, forming froth, and doing the greater part of the work with the froth accumulated and thus producing an agitating and compressing effect on the washing which 10 greatly facilitates the cleansing process making the washing an easier task, all, as more fully set forth in the claims.

In referring to the drawings, which are hereby made a part of this application, Figure 1 shows a central sectional view of the body portion of my device. Fig. 2 shows a view of the top or lid to the container, and the top of the conduits and valves. Fig. 3 shows a somewhat enlarged view of the 20 under side of a valve and a small portion of the bottom of the container.

Referring more particularly to the drawings, 4 shows the tub of my device which is made in any desirable way to hold water.

5 is a vertical reciprocating container for the articles to be washed, and is operated by the lever 6 through the piston 7 as will be readily seen from the drawings. I have arranged a stop 8 for holding the container 25 to its upper limit when desired. In the bottom of the container any desired number of perforations 9 are made as also larger perforations 10 in the corners of the bottom of the container. These larger perforations 30 are each provided with a hinged valve 11 having a spring 12 for holding the valve normally closed. In the corners of the container there are conduits 13 formed by fastening inner plates 14 to the sides and bottom of 40 the container and extending approximately the full height of same to permit air and froth to be drawn past the washing and below the container at each upstroke thus giving the accumulated froth which forms, on 45 top of the container direct passage below the container on the upward stroke. On the inner side of the container I have arranged a spring actuated dasher to aid in the operation. In this instance, I have shown the 50 cross 15 and the spring 16. A lid 17, having perforations 17^a, is arranged to fit the top of the container and fastened thereon, completely covering the container excepting the 55 conduits which are open at the top as shown in Fig. 2. The sides of the container extend

slightly above the lid as shown by 18, and considerably below the bottom as shown by 19, and these sides fit the inside of the tub so that water or air cannot readily pass up between same.

In operating my machine, only enough hot water is used to slightly cover the container at its lowest limit. Then the washing and soap are put in the container and the dasher and lid placed in their positions. 65 The lever is oscillated to the proper degree. It is easy to be seen that the washing lying on the bottom of the container will not readily let the water pass downward through the perforations 9 when the container is 70 forced in the upward stroke, but a vacuum will be formed below the container and the air and surplus froth will pass down through the valves and fill the vacuum. As the container is again returned toward its lower 75 position, this air is forced through the container and agitating the washing, forming froth and making easy work. As the work progresses the superfluous suds will also be drawn down through the valves and again 80 used. The extension 19 holds the froth and air just below the bottom of the container and compressing them through the washing on each downward stroke. From the foregoing it is easy to be seen that only the 85 proper amount of water need be retained in and moved with the container to produce the proper amount of froth as the articles in the container close the perforations 9 to a large extent on the upward stroke and that 90 the work is accomplished with a great saving of energy and that the device will work evenly and smoothly at any desired speed and yet is a very simple device. Then the lever 6 may be caught by any common stop 95 at 8 and the washing held out of the water for removing same from the container.

Having thus described my invention, what I claim as new and desire Letters Patent on is:

1. In a machine of the class described, a tub, a reciprocating container in the tub, open top conduits in the container and spring actuated valves in the conduits.

2. In a machine of the class described, a 105 tub, a reciprocating container in the tub, conduits in the container and valves in the conduits.

Ladora, Iowa, June 18th, 1923.

FRANK J. GENSLEY.
